UNITED STATES PATENT OFFICE.

JAMES ALFRED KENDALL, OF STREATHAM, LONDON, ENGLAND.

TREATMENT OF CHLORIDS OF THE ALKALI METALS FOR THE OBTAINMENT OF USEFUL PRODUCTS THEREFROM.

1,124,143.

Specification of Letters Patent.

Patented Jan. 5, 1915.

No Drawing.

Application filed November 22, 1913. Serial No. 802,517.

To all whom it may concern:

Be it known that I, JAMES ALFRED KENDALL, a subject of the King of Great Britain, residing at 99 Babington road, Streatham, London, England, have invented a new and useful Treatment of Chlorids of the Alkali Metals for the Obtaining of Useful Products Therefrom, of which the following is a specification.

17 This invention has for its object to obtain useful products from chlorids of the alkali metals and especially from chlorid of sodium and chlorid of potassium.

It has already been proposed to reduce 15 the tungstates and molybdates of the alkalis by means of carbon at about 1200° centigrade with evolution of the vapor of the alkali metal together with carbon monoxid. Further the addition of metallic tungsten, 20 molybdenum, titanium and the like has been proposed to facilitate the reaction between potash or soda, carbon, and nitrogen, yielding the cyanid of the alkali metal.

The novelty and importance of the present invention however comprises the utilizing 25 of common salt or chlorid of potassium, and the cyclic character of the entire process, the tungsten or molybdenum being used repeatedly and in the same vessel, that is to 30 say according to this invention, a definite stock of tungsten or molybdenum is repeatedly used in order to effect the transformation of unlimited quantities of alkali-metal chlorid into various useful products as hereinafter fully described.

According to this invention, which may be carried out in two stages, I treat the chlorid 35 of the alkali metal in the first stage in a vessel of nickel or cobalt or principally of 40 nickel or cobalt at a high temperature with vapor of water, in the presence of molybdenum or tungsten (which latter metals may be defined as intermediate metals of the chromium series; the fully oxidized compounds of which form fusible salts with the 45 alkalis) the said intermediate metals being preferably finely divided.

In carrying out the above reaction, and especially when using tungsten, some of the 50 water vapor may if desired be passed through the heated tungsten before the chlorid of the alkali metal is allowed to enter the vessel. A partial oxidation of the tungsten then takes place, which facilitates 55 the subsequent formation of tungstate of the

alkali metal. This first stage of the process may be carried out at temperatures which can be varied from a red heat up to about 1100° centigrade. In the second stage of the process the said molybdate, or tungstate, 60 is then reduced, at a high temperature (say about from 1200° to 1300° centigrade) by means of carbon, so that alkali metal is driven off with carbon monoxid, and these also can be collected, or utilized, in any desired way. Metallic molybdenum, or tungsten, remains in the vessel and this can then be again utilized for treatment of a fresh charge of the chlorid of the alkali metal 65 with vapor of water.

According to a modification of the process, I employ molybdate, or tungstate, of barium together with carbon, these materials being heated to a high temperature, and I run in the fused chlorid of the alkali 70 metal in a properly regulated manner. Vapor of the alkali metal and carbon monoxid are evolved and, after the reaction is complete, a mixture of chlorid of barium and metallic molybdenum, or tungsten, remains in the vessel and, on this being treated, at the necessary temperature, with water 75 vapor, hydrogen and hydrochloric acid are given off and molybdate, or tungstate, of barium is regenerated for use in treating 80 further quantities of the chlorid of alkali metal.

The vessel or retort in which the reaction takes place may be heated in any convenient way, for example by means of a furnace flooded with flame obtained from the combustion of hydrocarbon gas, or oil. The said vessel may be provided with a tube extending to near the lower end for the admission of the water vapor, and with 90 a funnel and tube for the admission of the fused chlorid of the alkali metal to near the lower part of the vessel, and tubes are also provided for the outlet of the hydrogen and hydrochloric acid and the mixture 95 of alkali metal vapor and carbon monoxid. These tubes where subjected to the furnace heat should be made of nickel or cobalt. The vessel is provided with a closable opening for the introduction of the carbon and 100 the closure for this opening can be a stopper of nickel or cobalt.

The apparatus described is a convenient means for carrying out the process according to this invention but the invention is 110

not limited thereto as any other suitable or convenient apparatus may be employed.

As examples of the utilization of the gaseous products, I mention the absorption of 5 the hydrochloric acid by water to produce ordinary liquid hydrochloric acid, and the collection of the hydrogen in a gas holder and the passing of the mixture of the vapor of the alkali metal and carbon monoxid 10 into a condenser to condense the alkali metal, or the burning of the gaseous mixture with the necessary access of air to form carbonate of the alkali metal, which may be allowed to deposit in a flue, or be otherwise 15 collected.

If desired, the gases containing the vapor of alkali metal can be used for the production of cyanids by passing the said gases together with nitrogen into an apparatus 20 charged with carbon and heated to a high temperature and suitable for the synthetic production of cyanids. Or I may use the retort, already referred to for producing the cyanids. In this case a sufficiently large 25 charge of carbon is passed into the said retort to form the cyanid in the presence of nitrogen, the requisite amount of nitrogen being passed into the said retort either through the pipe which is otherwise used 30 for passing the water vapor into the retort, or if preferred a second pipe may be provided for the nitrogen.

Although tungsten is referred to throughout the claims, it is to be understood that 35 molybdenum may be substituted therefor in place of tungsten.

What I claim is:—

1. The process of treating alkali-metal chlorids, which consists in subjecting alkali 40 metal chlorid at a high temperature to the action of aqueous vapor in the presence of an intermediate metal of the chromium series, subsequently reacting on the resulting product at a high temperature with carbon 45 to obtain the intermediate metal and re-using the intermediate metal so obtained for the treatment of a fresh charge of alkali-metal chlorid.

2. The process of treating alkali-metal

chlorids, which consists in subjecting alkali-metal chlorid at a high temperature to the action of aqueous vapor in the presence of tungsten, subsequently reacting on the resulting product at a high temperature with carbon to obtain the tungsten and re-using 55 the tungsten so obtained for the treatment of a fresh charge of alkali-metal chlorid.

3. The process of treating alkali-metal chlorids, which consists in subjecting alkali-metal chlorid at a high temperature to the 60 action of aqueous vapor in the presence of tungsten in a finely divided condition, subsequently reacting on the residue at a high temperature with carbon to obtain the tungsten and re-using the tungsten so obtained 65 for the treatment of a fresh charge of alkali-metal chlorid.

4. The herein described cyclic process of treating alkali-metal chlorids, which consists in first subjecting an alkali-metal 70 chlorid at a high temperature to the action of aqueous vapor in the presence of tungsten, and subsequently reacting on the tungsten of the alkali-metal so obtained with carbon to produce metallic tungsten and 75 alkali-metal, the said tungsten being then re-used for treating a fresh charge of alkali-metal chlorid.

5. The treatment of alkali-metal chlorid in a cyclic process of two stages, the first 80 stage consisting in subjecting alkali-metal chlorid at a high temperature to the action of aqueous vapor in the presence of tungsten in a finely divided condition until substantially all the hydrogen and hydrochloric acid are revolved, and the second stage consisting in reacting on the residue at a high temperature with carbon to obtain the tungsten, the tungsten so obtained being then re-used for the treatment of a fresh 85 charge of alkali-metal chlorid.

In testimony whereof I have signed my name to this specification in the presence of two subscribing witnesses.

JAMES ALFRED KENDALL.
